(57) **CLAIM**

The ornamental design for a robot gripper, as shown and described.

DESCRIPTION

FIG. 1 is a front view of a robot gripper;
FIG. 2 is a rear view thereof;
FIG. 3 is a right side view thereof;
FIG. 4 is a left side view thereof;
FIG. 5 is a top view thereof;
FIG. 6 is a bottom view thereof;
FIG. 7 is an upper perspective view thereof;
FIG. 8 is an upper perspective view thereof in an expanded position;
FIG. 9 is a lower perspective view thereof in an expanded position; and,
FIG. 10 is a lower perspective view thereof.
